DISPENSING BRUSH FOR CLEANING UPHOLSTERY OR THE LIKE

Sheldon David Hulsh, 530 Park Ave., New York, N.Y.

Filed Sept. 29, 1960, Ser. No. 62,307

Term of patent 14 years

(Cl. D9—2)

FIG. 1.

FIG. 2.

FIG. 3.

FIG. 4.

FIG. 5.

FIGURE 1 is a side elevational view of a dispensing brush for cleaning upholstery or the like showing my new design;

I claim:

The ornamental design for a dispensing brush for cleaning upholstery or the like, substantially as shown.
